UNITED STATES PATENT OFFICE

WILLIAM JESSOP, OF GRAYS, ENGLAND, ASSIGNOR OF ONE-THIRD TO DRUMS, LIMITED,
AND ONE-THIRD TO THE INTERNATIONAL PAINT AND COMPOSITIONS COMPANY,
LIMITED, BOTH OF LONDON, ENGLAND

GUARD

Application filed April 23, 1930, Serial No. 446,749, and in Great Britain April 30, 1929.

This invention relates to guards for presses and particularly power presses, stamps, hammers and the like machines of the type in which the guard member is adapted to move outward towards the operative engaged in feeding the machine, so that in the event of the operative not removing his hands at the appropriate time from the danger zone the guard member will operate to force them away from the machine.

In guards of this kind the guard member has hitherto been arranged to be operated by some moving part of the machine and in such manner that the same degree of motion is imparted to it whether or not an obstruction, for instance the hands of the operative, is in the path of its motion, with the result that the guard member if associated with a quick acting machine is subjected to considerable stresses.

According to the present invention a guard member of the kind in question is associated with means adapted to constrain it to move, in setting the press or the like in motion, into a normal safe position in which it will preclude the hands of the operative entering the danger zone, and means adapted by the operation of the press, in the event of the guard member being restrained from assuming the said position, to move the guard member outward and remove the obstruction.

In one construction in accordance with the invention the pedal by which the press or like machine is set in motion is connected by rods, links or the like with the guard member and with the clutch by means adapted to constrain the guard member to move into the normal safe position before the clutch is engaged and a driving connection is provided between some moving part of the press and the guard member normally in engagement to cause the guard member to force any obstruction to its motion away from the danger zone of the machine, the said driving

connection being interrupted only in the event of the guard being permitted to move into its normal safe position under the action of the pedal.

The invention will be described further in detail and by way of example with reference to the accompanying drawings in which:—

Figure 1 is a front elevation of one construction showing the guard in the open position,

Figure 2 is a side elevation thereof, and Figure 3 is a further side elevation.

Figure 4 is a side elevation of a further construction in accordance with the invention,

Figure 5 is a front elevation of the construction illustrated in Figure 4,

Figure 6 illustrates the normal operation of the construction illustrated in Figures 4 and 5, while

Figure 7 illustrates the operation thereof when opposition to its operation is encountered.

In the constructions illustrated, the guard member comprises a main frame, a shaft 1 pivotally secured through the bracket lugs 2 to the body of the press 3 and including side members 4 extending in a downward direction from the shaft and connected by bars 5.

Adjacent to their lower extremities and in the vicinity of the gap 6 of the press to the main frame is pivotally connected by the bar 7 a second frame comprising side members 8 connected together by bars 9, adapted when the side members of the two frames are substantially in register, to preclude access to the gap of the press. In the construction illustrated in Figure 3, to the second frame is connected a lever 10 pivotally connected with a rod 11 having at its upper extremity a connection 12 adapted to permit a certain degree of lost motion between the rod 11 and the lever 13. The lever 13 is formed with a recess

50

55

60

65

65

75

80

85

90

14 normally engaging an eccentric pin 15 associated with the main shaft 16 of the press in such manner that when the recess is in engagement with the pin, the main frame of 5 the guard will be forcibly moved about its axis in an outward direction and away from the press as the ram descends.

The motion of the second of the two frames forming the guard member is secured in the 10 construction illustrated in Figures 1 and 2 by providing thereon a lever 17 adapted to bear against a roller 18 secured to the lever 19, mounted on a pivot 20 about which it is adapted to rock in opposition to the spring 21. Also mounted on the pivot 20 is the cam lever 22 connected with the rod 23 the forward end 24 of which bears against the 15 first mentioned guard frame, the cam lever being caused to move about its pivotal connection with the body of the press by the action of the pedal lever 25, pivoted at 26 constrained against the spring 27 and connected at 28 with the rod 29 connected to the lever 30 provided with a roller 31 bearing against the cam lever 20 and pivoted at 32 with the lever 19, and at 25 33 with the rod 34 connected through the lost motion connection 35 with the clutch actuating device 36 of the press.

In operating the press the pedal lever 25 is depressed, and the main guard frame (see dotted position in Figure 2) is pushed outward to a degree which will constrain the second guard frame to move into the "safe" 30 position.

Should the guard member be permitted to assume the "safe" position the motion of the rod 11 connecting the second frame with the lever 13 will release the recess 14 in the lever 20 from engagement with the eccentric pin 15, and continue depression of the pedal lever 25 to cause the clutch of the press to be engaged will not result in further motion being imparted to the guard member.

If, on the other hand, an obstruction prevents the second frame from assuming the normal "safe" position, the recess 14 in the lever 13 will not be released from engagement with the eccentric pin 15, and both the main guard frame and the second guard frame will 45 be caused to move outward consequent on the motion of the eccentric pin 15 to the extreme right hand position shown dotted in Figure 3 and the second frame will be caused to move outward while the roller 31 bearing upon the 50 cam lever 22 associated with the second frame will constrain it to grip the hand or other obstruction to its motion under the action of the spring 21.

In the construction illustrated in Figures 60 4, 5, 6 and 7, the second frame is pivotally connected at 37 with the lever 38 to the upper portion of which is pivotally connected at 39 one end of a link 40, the other end of which is pivotally connected at 41 with the main 65 frame 4.

Also pivotally connected at 39 with the lever 38 is one end of the link 42 provided adjacent to its other end with a slot 43 adapted to engage a pin 44 in the lever 45 coaxially mounted on the shaft 1 with the main frame. 70

The lever 45 is provided with a cam faced projection 46 adapted to engage and be disengaged from contact with the end 47 of the lever 38 and is pivotally connected by means of the clamp 48 with a push rod 49 engaging at its end 50 the pin 51 eccentrically mounted on the operating shaft 16. 75

In the operation of the guard the main frame is constrained to move against the action of the spring 52 connected at 53 with a stationary part of the machine and at 54 with the main frame. 80

For regulating the position of the main frame with respect to the body of the press, an adjustable stop is provided comprising a bracket 55 and an adjustment screw 56, one end of which is adapted to bear against the upper portion of the main frame. 85

The operation of this construction will be understood by reference more particularly to Figures 6 and 7. Figure 4 illustrates the position in which the danger zone of the machine is exposed and in the event of there being no opposition to movement of the second frame, rotation of the operating shaft 90 16 will, by actuation of the push rod 49, cause the lever 45 to be depressed and the cam faced projection 46 to exert pressure upon the end 47 of the lever 38 thereby depressing it and causing the second frame to be rotated into the 95 normal safe position, illustrated in Figure 6.

In this position the cam faced projection 46 is disengaged from the end 47 of the lever 38.

Should resistance to motion of the second frame be encountered (see Figure 7) such resistance will preclude the disengagement of the cam faced projection and further rotation of the shaft 16 will cause thrust to be transmitted through the link 40 to the main frame 4 thereby moving the latter away from the body of the machine in opposition to the spring 52 and removing the obstruction from the danger zone. 100

The above description is furnished for the purpose of describing the nature of the invention and while certain constructions in accordance with the invention have been particularly described by way of example various changes may be made in the constructional arrangements and details without exceeding the scope of the invention. 110

Having now described my invention, what I claim as new and desire to secure by Letters Patent is:—

1. A guard for power presses and like machines comprising a main frame pivotally connected with the body of the machine, a cam member, a pivotal connection between said cam member and a stationary part of the machine, a push rod bearing at one end against 125

130

the main frame and pivotally connected at its other end with the cam member, a lever coaxially mounted with the cam member, a spring connected at one end with said lever, 5 and at its other end with a stationary part of the machine, a second lever pivotally connected with one end of said lever, a roller mounted on the other end of said second mentioned lever co-operating with the face of the cam member, a rod connected at one end with said second mentioned lever, a pedal lever, a pivotal connection between the other end of the said rod and the pedal lever adapted, upon actuation of the pedal lever, to rotate the said 10 second mentioned lever about its pivotal connection with the first mentioned lever and cause the roller bearing against the face of the cam member to oscillate the cam and cause the push rod to move the main frame away from the body of the machine and towards the operator engaged in feeding the same, a second frame 15 pivotally connected with the main frame, a two armed lever connected with the second frame, a roller mounted on the end of the first mentioned lever remote from its pivotal connection with the second mentioned lever adapted in moving the main frame away from the body of the machine to co-operate with said two armed lever and cause the roller bearing against the face of the cam member to oscillate the cam and cause the push rod to move the main frame away from the body of the machine and towards the operator engaged in feeding the same, a second frame 20 pivotally connected with the main frame, a two armed lever connected with the second frame, a roller mounted on the end of the first mentioned lever remote from its pivotal connection with the second mentioned lever adapted in moving the main frame away from the body of the machine to co-operate with said two armed lever and cause the roller bearing against the face of the cam member to oscillate the cam and cause the push rod to move the main frame away from the body of the machine and towards the operator engaged in feeding the same, a second frame 25 pivotally connected with the main frame, a two armed lever connected with the second frame, a roller mounted on the end of the first mentioned lever remote from its pivotal connection with the second mentioned lever adapted when the main frame is moving away from the body of the machine to co-operate with said two armed lever and cause the roller bearing against the face of the cam member to oscillate the cam and cause the push rod to move the main frame away from the body of the machine and towards the operator engaged in feeding the same, a second frame 30 pivotally connected with the main frame, a two armed lever connected with the second frame, a roller mounted on the end of the first mentioned lever remote from its pivotal connection with the second mentioned lever adapted in moving the main frame into a position in which it will preclude the hands of the operator entering the danger zone, a link mechanism connecting the said frames with a moving part of the machine adapted, in the event of the second frame encountering opposition to assuming the said position, to impart to the main frame further motion in an outward direction 35 and away from the machine.

425

3. A guard for power presses and like machines having a working space constituting a danger zone for the operator engaged in feeding the same, comprising a main frame, a second frame pivotally connected with said main frame, movable elements interconnecting the second frame with a moving part of the machine adapted in consequence of movement of the said moving part to communicate motion therefrom to the second frame thereby moving the same away from the body of the machine and towards the operator engaged in feeding the same into a position in which it will preclude the hands of the operator entering the danger zone, a link pivotally connected at one end with the main frame, a recess adjacent to the other end of the link, a pin eccentrically mounted in the operating shaft of the machine adapted to engage with in the recess, a rod connected at one end through a lost motion connection with the link, a lever connected with the second frame, a pivotal connection between the other end of the said rod and the said lever adapted in the event of the second frame encountering opposition to assuming the said position, to impart to the main frame further motion in an outward direction and away from the machine thereby moving the second frame beyond the said position.

430

2. A guard for power presses and like machines having a working space constituting a danger zone for the operator engaged in feeding the same, comprising a main frame pivotally connected with the body of the machine, a cam member pivotally connected with a stationary part of the machine, a push rod bearing at one end against the main frame and pivotally connected at its other end with the cam member, a lever coaxially mounted with the cam member, a spring connected at one end with said lever, and at its other end with a stationary part of the machine, a second lever pivotally connected with one end of the first mentioned lever, a roller mounted on the other end of said second mentioned lever co-operating with the face of the cam

member, a rod connected at one end with said second mentioned lever, a pedal lever, a pivotal connection between the other end of the said rod and the pedal lever adapted, upon actuation of the pedal lever to communicate movement to the rod thereby rotating the said second mentioned lever about its pivotal connection with the first mentioned lever and causing the roller bearing against the face of the cam member to oscillate the cam thus causing the first mentioned push rod to move the main frame away from the body of the machine and towards the operator engaged in feeding the same, a second frame 70 pivotally connected with the main frame, a two armed lever connected with the second frame, a roller mounted on the end of the first mentioned lever remote from its pivotal connection with the second mentioned lever adapted in moving the main frame away from the body of the machine to co-operate with said two armed lever and move the second frame into a position in which it will preclude the hands of the operator entering the danger zone, and link mechanism connecting the said frames with a moving part of the machine adapted, in the event of the second frame encountering opposition to assuming the said position, to impart to the main frame further motion in an outward direction 75 and away from the machine.

80

3. A guard for power presses and like machines having a working space constituting a danger zone for the operator engaged in feeding the same, comprising a main frame, a second frame pivotally connected with said main frame, movable elements interconnecting the second frame with a moving part of the machine adapted in consequence of movement of the said moving part to communicate motion therefrom to the second frame thereby moving the same away from the body of the machine and towards the operator engaged in feeding the same into a position in which it will preclude the hands of the operator entering the danger zone, a link pivotally connected at one end with the main frame, a recess adjacent to the other end of the link, a pin eccentrically mounted in the operating shaft of the machine adapted to engage with in the recess, a rod connected at one end through a lost motion connection with the link, a lever connected with the second frame, a pivotal connection between the other end of the said rod and the said lever adapted in the event of the second frame encountering opposition to assuming the said position, to impart to the main frame further motion in an outward direction and away from the machine thereby moving the second frame beyond the said position.

100

4. A guard for power presses and like machines having a working space constituting a danger zone for the operator engaged in feeding the same, comprising a main frame piv-

105

totally connected with the body of the machine, a cam member pivotally connected with a stationary part of the machine, a push rod bearing at one end against the main frame and pivotally connected at its other end with the cam member, movable elements interconnecting the cam member with a moving part of the machine, adapted in consequence of movement of the said moving part to oscillate said cam member thereby causing the push rod to impart motion to the main frame away from the body of the machine and towards the operator engaged in feeding the same, a second frame pivotally connected with the main frame, movable elements interconnecting the second frame with a stationary part of the machine adapted in consequence of the said motion of the main frame away from the body of the machine to move the second frame into a position in which it will preclude the hands of the operator entering the danger zone, a link pivotally connected at one end with the main frame, a recess adjacent to the other end of the link, a pin eccentrically mounted in the operating shaft of the machine engaging within the recess, a rod connected at one end through a lost motion connection with the link, a lever connected with the second frame, a pivotal connection between the other end of the last mentioned rod and the said last mentioned lever adapted in the event of the second frame encountering opposition to assuming the said position, to impart to the main frame further motion in an outward direction and away from the machine thereby moving the second frame beyond the said position.

5. A guard for power presses and like machines having a working space constituting a danger zone for the operator engaged in feeding the same, comprising a main frame pivotally connected with a stationary part of the machine, a lever pivotally connected at one end with a stationary part of the machine and at its other end with a moving part of the machine, a second frame pivotally connected with the main frame, a second lever pivotally connected at one end with the second frame, a link pivotally connected at one end with the said second lever and provided at its other end with an elongated slot, a stop on the first mentioned lever co-operating with the elongated slot, a cam faced member associated with the first mentioned lever adapted in setting the machine into operation to co-operate with the end of the second mentioned lever remote from the second frame in order to move the second frame outward away from the body of the machine and towards the operator engaged in feeding the same into a position in which it will preclude the hands of the operator from entering the danger zone, a second link pivotally connected at one end coaxially with said first mentioned link and at its other end with the main frame adapted in the event of the second frame encountering opposition to assuming the said position to cause the driving connection between the cam faced member and the end of the second mentioned lever to be continued and positive motion to be imparted to the said frames whereby the second frame is moved in an outward direction beyond the said position.

6. A guard for power presses and like machines having a working space constituting a danger zone for the operator engaged in feeding the same, comprising a main frame pivotally connected with the body of the machine, a cam member pivotally connected with a stationary part of the machine, a push rod bearing at one end against the main frame and pivotally connected at its other end with the cam member, a lever coaxially mounted with the cam member, a spring connected at one end with said lever, and at its other end with a stationary part of the machine, a second lever pivotally connected with one end of said lever, a roller mounted on the other end of said second mentioned lever co-operating with the face of the cam member, a rod connected at one end with said second mentioned lever, a pedal lever, a pivotal connection between the other end of the said rod and the pedal lever adapted upon actuation of the pedal lever to communicate movement to the rod thereby rotating the said second mentioned lever about its pivotal connection with the first mentioned lever and causing the roller bearing against the face of the cam member to oscillate the cam thus causing the

push rod to impart motion to the main frame away from the body of the machine and towards the operator engaged in feeding the same, a second frame pivotally connected with the main frame, movable elements interconnecting the second frame with a stationary part of the machine adapted in consequence of the said motion of the main frame away from the body of the machine to move the second frame into a position in which it will preclude the hands of the operator entering the danger zone, a link pivotally connected at one end with the main frame, a recess adjacent to the other end of the link, a pin eccentrically mounted in the operating shaft of the machine engaging within the recess, a rod connected at one end through a lost motion connection with the link, a lever connected with the second frame, a pivotal connection between the other end of the last mentioned rod and the said last mentioned lever adapted in the event of the second frame encountering opposition to assuming the said position, to impart to the main frame further motion in an outward direction and away from the machine thereby moving the second frame beyond the said position.

7. A guard for power presses and like machines having a working space constituting a danger zone for the operator engaged in feeding the same, comprising a main frame pivotally connected with a stationary part of the machine, a lever pivotally connected at one end with a stationary part of the machine and at its other end with a moving part of the machine, a second frame pivotally connected with the main frame, a second lever pivotally connected at one end with the second frame, a link pivotally connected at one end with the said second lever and provided at its other end with an elongated slot, a stop on the first mentioned lever co-operating with the elongated slot, a cam faced member associated with the first mentioned lever adapted in setting the machine into operation to co-operate with the end of the second mentioned lever remote from the second frame in order to move the second frame outward away from the body of the machine and towards the operator engaged in feeding the same into a position in which it will preclude the hands of the operator from entering the danger zone, a second link pivotally connected at one end coaxially with said first mentioned link and at its other end with the main frame adapted in the event of the second frame encountering opposition to assuming the said position to cause the driving connection between the cam faced member and the end of the second mentioned lever to be continued and positive motion to be imparted to the said frames whereby the second frame is moved in an outward direction beyond the said position.

8. A guard for power presses and like ma-

- chines having a working space constituting a danger zone for the operator engaged in feeding the same, comprising a guard member, movable elements interconnecting the guard member with a moving part of the machine adapted in consequence of movement of the said moving part to communicate motion therefrom to the guard member thereby moving the same outward away from the body of the machine into a position in which it will preclude the hands of the operator entering the danger zone, and further movable elements interconnecting the guard member with a moving part of the machine adapted in the event of the guard member encountering opposition to assuming the said position to communicate further motion thereto from the machine and to move it positively in an outward direction beyond the said position.
8. A guard for power presses and like machines having a working space constituting a danger zone for the operator engaged in feeding the same, comprising a main frame, a second frame associated with the main frame, movable elements interconnecting the second frame with a moving part of the machine adapted in consequence of movement of the said moving part to communicate motion therefrom to the second frame thereby moving the same away from the body of the machine and towards the operator engaged in feeding the same into a position in which it will preclude the hands of the operator entering the danger zone, and further movable elements interconnecting the said frames with a movable part of the machine adapted in the event of the second frame encountering opposition to assuming the said position, to communicate from the machine to the said frames motion in an outward direction beyond the said position.
9. A guard for power presses and like machines having a working space constituting a danger zone for the operator engaged in feeding the same, comprising a main frame pivotally connected with the body of the machine, movable elements interconnecting the said main frame with a moving part of the machine and adapted in consequence of movement of the said moving part to communicate motion therefrom to the main frame thereby moving the same away from the body of the machine and towards the operator engaged in feeding the same, a second frame pivotally connected to the main frame, further movable elements interconnecting the second frame with a stationary part of the machine adapted in consequence of the said movement of the main frame to cause the second frame to move into a position in which it will preclude the hands of the operator entering the danger zone and further movable elements interconnecting the frames with a moving part of the machine adapted in the event of the second frame encountering re-
- sistance to its motion to move the said frame positively in an outward direction beyond the said position.
10. A guard for power presses and like machines having a working space constituting a danger zone for the operator engaged in feeding the same, comprising a main frame pivotally connected with the body of the machine, movable elements interconnecting the main frame with a moving part of the machine adapted in consequence of movement of the said moving part to communicate motion therefrom to the main frame thereby moving the same away from the body of the machine towards the operator engaged in feeding the same, a second frame pivotally connected with the main frame, further movable elements interconnecting the second frame with a stationary part of the machine and adapted in consequence of the said motion of the main frame to move the second frame into a position in which it will preclude the hands of the operator entering the danger zone, a further movable element connected with the main frame and releasably connected with a moving part of the machine, and a rod interconnecting the said movable element with the second frame adapted to cause the movable element to be released from engagement with the said moving part in the event of the second frame reaching the said position and in the event of the second frame encountering resistance to its motion to cause the movable element to continue in engagement with the said moving part thereby communicating positive motion to the frames in an outward direction beyond the said position.
11. A guard for power presses and like machines having a working space constituting a danger zone for the operator engaged in feeding the same, comprising a main frame pivotally connected with the body of the machine, a cam member pivotally connected with a stationary part of the machine, a push rod bearing at one end against the main frame and pivotally connected at its other end with the cam member, movable elements interconnecting the cam member with a moving part of the machine and adapted in consequence of movement of the said moving part to oscillate the said cam member thereby causing the push rod to move the main frame away from the body of the machine and towards the operator engaged in feeding the same, a second frame pivotally connected with the main frame, movable elements interconnecting the second frame with a stationary part of the machine and adapted in consequence of the said motion of the main frame away from the body of the machine to move the second frame into a position in which it will preclude the hands of the operator entering the danger zone and further movable elements

interconnecting the frames with a moving part of the machine adapted in the event of the second frame encountering opposition to assuming the said position to communicate from the said moving part to the main frame further motion in an outward direction away from the machine thereby moving the second frame positively beyond the said position.

10 In testimony whereof I have signed my name to this specification.

WILLIAM JESSOP.
